CLAIM

The ornamental design for a micrometer, as shown and described.

DESCRIPTION

FIG. 1 is a front, left side, top perspective view of the micrometer showing our new design;

FIG. 2 is a front, right side, top perspective view thereof;

FIG. 3 is a front elevational view thereof;

FIG. 4 is a rear elevational view thereof;

FIG. 5 is a right side elevation view thereof;

FIG. 6 is a left side elevational view thereof;

FIG. 7 is a top plan view thereof; and,

FIG. 8 is a bottom plan view thereof.

The dashed broken lines in the drawings depict portions of the micrometer that form no part of the claimed design.

1 Claim, 6 Drawing Sheets
